(57) **CLAIM**

The ornamental design for a curtain for a rolling walker, as shown and described.

DESCRIPTION

FIG. 1 is a top perspective front view of a curtain for a rolling walker;

FIG. 2 is a top perspective rear view of the curtain illustrated in FIG. 1;

FIG. 3 is a front elevation view of the curtain illustrated in FIG. 1

FIG. 4 is a rear elevation view of the curtain illustrated in FIG. 1;

FIG. 5 is a side elevation view of the curtain illustrated in FIG. 1; and,

FIG. 6 is a top view of the curtain illustrated in FIG. 1. The dashed lines showing the rolling walker and portions of the curtain depict environment and form no part of the claimed design.

1 Claim, 3 Drawing Sheets
